HEATING SYSTEM

Claude G. Bordeaux, Albany, N. Y.

Application April 29, 1932, Serial No. 608,266

11 Claims. (Cl. 237—12.3)

My invention more particularly relates to a steam heating system utilizing a closed circuit and employing a relatively small amount of fluid. My invention is particularly useful for the heating of automobiles or other vehicles where the exhaust gases from the internal combustion engine may be utilized for heating although it will, of course, be understood that my invention is not limited to this particular use.

One of the objects of my invention is a heating system in which the pressure and the temperature are automatically maintained substantially constant.

A further object of my invention is a heating system which is simple in construction and reliable in operation.

Other objects of my invention will appear in the specification.

My invention will best be understood by reference to the accompanying drawings in which I have illustrated a preferred embodiment and in which—

Fig. 1 is a side view partially broken away illustrating somewhat diagrammatically a heating system embodying my invention;

Fig. 2 is a sectional view through a liquid supply reservoir to which the water is conducted from the radiator;

Fig. 3 is a vertical sectional view through a device comprising a chamber to which the liquid is conducted from the supply reservoir and from which it is led to the heater;

Fig. 4 is a detail view of the lower portion of the pipe which leads from the radiator to the liquid supply reservoir;

Fig. 5 is a side view partially in section of the connection leading from the regulating chamber to the heater; and

Fig. 6 is a sectional detail illustrating the check valve.

Like reference characters indicate like parts throughout the drawings.

Referring now to the drawings, 10 is a steam generator which, in the embodiment illustrated, is in the form of a coil enclosed in a housing 11 forming a part of the exhaust pipe 12 leading from an internal combustion engine.

The device embodying my invention may readily be applied to the ordinary exhaust pipe 12 of an automobile. The exhaust pipe may conveniently be cut as at 13 and the exhaust end 121 of the exhaust pipe may be moved to the left, as viewed in Fig. 1 and the steam generator and associated parts applied directly to the exhaust pipe. Section 111 which is in the form of a tube is secured by a flange 112 to the housing 11 and abuts against the cut section 12 of the exhaust pipe. The housing is also provided with a sleeve 113, the end of which is preferably serrated as at 114 and is received over the exhaust end 121

of the exhaust pipe and is frictionally secured thereto. The heater may conveniently be secured to the pipe section 12 by a sleeve 115 which is secured in position by a clamping collar 116.

The steam generator 10 is connected by a steam supply pipe 14 to a radiator indicated generally at 15. While the particular form of radiator constitutes no part of my present invention, I have, for convenience of illustration, shown a radiator which comprises a coil or pipe 16 which extends back and forth across the radiator and to which is connected a plurality of radiating fins 17. Air may be forced over the radiator to the interior of a car by a fan 18 which is driven by a suitable motor 19 which may be supported by brackets 20 which are in turn attached to the wall 21 of the body of a car. Adjustable vanes 22 may be utilized for directing the air from the radiator to desired points within the vehicle. The radiator is illustrated within the body of a car, and while the relations of the remaining portions of the heating system are not illustrated, it will be understood that they are mounted on the vehicle without the closed body.

The water supply reservoir 23, which is located at a lower level than the radiator, is connected thereto by a pipe 24 preferably jointed as at 25 and extending to the lower portion of the reservoir, as best shown in Fig. 2, the lower end of said pipe preferably being curved upwardly as 30 at 241 and provided at its end with a seat 26 in which is received a check valve 27, preferably in the form of a ball. A cap 28 provided with openings 29 may be secured to the end of the pipe by any suitable means, such as a cotter pin 30 and forms a housing for the ball valve. The pipe 24 is preferably welded to the wall of the reservoir as at 31 to form a fluid-tight joint. The reservoir may conveniently be closed by a bottom plate 32 which is also welded around its periphery to the lower wall 33 of the reservoir. It will be understood that the water level in the reservoir 23 is normally located above the bent end 241 of the inlet tube.

In accordance with my invention, a device is interposed between the liquid supply reservoir and the steam generator for controlling the flow of water from the reservoir to the generator. In the embodiment of my invention illustrated, such device comprises a chamber 34 connected by a pipe 35 to the lower end of the supply reservoir 23. The bottom of the chamber 34 is closed by a plate 36 provided with a conical valve seat 37 against which seats a poppet valve 38 which is mounted on the lower end of a valve stem 39, the valve being normally open. The upper end of the valve stem, in the embodiment illustrated, is connected to the closing plate 40 of a bellows diaphragm 41 which is located in said chamber and which is suitably secured to a cap 42. The

plate 40 normally rests against and is supported by standards 401 secured to or integral with the bottom plate 36.

The cap 42 is provided with a screw-threaded opening 43 in which is received a suitable screw-threaded plug 44 provided with an opening 45 by which the interior of the bellows diaphragm communicates with the atmosphere. The plug 44 is preferably provided with a downwardly extending stem 46 and a coil spring 47 surrounds said stem and engages the plug 44 while the lower end thereof engages the lower closing plate 40 of the bellows diaphragm. The compression in the spring 47 is so adjusted as normally to maintain the bellows diaphragm in expanded condition but permits the collapse of the diaphragm when a predetermined abnormal pressure is reached within the chamber 34.

While the ball valve 27 substantially prevents the return of fluid from the reservoir to the radiator, it does not entirely prevent such return for the reason that in practice, there is always a slight amount of slow leakage between a valve and its seat, particularly a ball valve of the character illustrated. The same is true of the check valve 53 hereinafter described. Such leakage eventually relieves the excess pressure in the supply reservoir. Furthermore, when the pressure in the generator drops due to the absence of water and the generation of steam therein, there is a drop in pressure on the under side of the valve 38, and such drop in pressure would create a variation in the differential in pressure on opposite sides of the valve which would also tend to open the valve.

The housing which encloses the chamber 34 is screw-threaded on its interior as at 48 and receives the screw-threaded end of a connection 49, the end of which is preferably secured to one end of a check-valve casing 50, as by silver brazing. The steam generating coil is preferably formed of a compound tubing comprising an inner tube 51, which is preferably formed of copper to withstand the corrosive effects of water in the steam generator, and an outer tube 52 which is preferably formed of steel which is well adapted to withstand the corrosive effect of the exhaust gases. The tubular heating element is preferably formed by placing a copper tube within the steel tube and then swaging the two tubes down together. The end of the copper tube is attached to the valve casing as by silver brazing. The check valve, in the embodiment illustrated, comprises a ball valve 53 which normally rests against a seat 54. While I have described water as the liquid medium which is converted into vapor in my system, it will, of course, be understood that other liquid media which are converted into vapor may be utilized.

The operation of the device embodying my invention will readily be understood from the foregoing description and is as follows—

Water may be introduced into the system through the joint 25 in the pipe 24 until the desired amount of water has been received in the supply reservoir, the chamber 34 and in the steam generator 10. As heretofore stated, the device embodying my invention operates as a closed system and utilizes a comparatively small amount of water, for example, 7 cubic inches for an ordinary automobile heater. The joint 25 is then closed and the system is ready for automatic operation. As soon as the steam generator 10 is subjected to the hot gases within the ex-

haust manifold, the small amount of water within the generator is vaporized and the steam is forced into the radiator. A substantially uniform pressure is then present throughout the system. I have found 75 pounds to be a convenient operating pressure when the device is used for heating an ordinary automobile although it will, of course, be understood that my invention is not limited to any given pressure.

It will be understood that the steam generator 10 operates intermittently and "flashes" or vaporizes all of the water that is in the generator at a given time. Now, as soon as the steam within the radiator condenses, the pressure within the radiator drops, for example to 72 pounds, when the system is operating at a normal pressure of 75 pounds, and the pressure in the steam generator also drops. The water level within the liquid supply reservoir 23 is intermediate the top and bottom thereof so that an air space is provided above the fluid therein. The original pressure within the supply reservoir 23 temporarily remains the same with the result that a small amount of water is forced past the check valve 53 into the generator. The water thus introduced is vaporized and the cycle of operations is repeated.

In case the temperature of the radiator and correspondingly the pressure within the radiator become unduly high due, for example, to the stopping of the fan motor which forces air over the radiator, the abnormal pressure is transmitted to the liquid supply reservoir and then to the chamber 34 and causes the collapse of the bellows diaphragm and correspondingly the upward movement of the valve stem 39 and the valve 38 is seated to prevent further flow of water from the chamber 34 to the steam generator 10. The danger of burning out the radiator which would otherwise be present, is, therefore, avoided.

While I have described my invention in its preferred embodiment, it is to be understood that the words which I have used are words of description and not of limitation and that changes within the purview of the appended claims may be made without departing from the true scope and spirit of my invention in its broader aspects.

What I claim is:

1. In a heating system, a vapor radiator, a vapor generator communicating therewith, a liquid supply reservoir located at a lower level than said radiator and at a higher level than said generator, means providing a communicating passage between said radiator and said reservoir, said reservoir being constructed and arranged to provide an air chamber above the liquid therein, a check valve constructed and arranged to substantially prevent the return of fluid from said reservoir to said radiator, means providing a communicating passageway between said reservoir and said generator, and means responsive to a predetermined pressure in the air chamber of said reservoir for preventing the flow of liquid therefrom to said generator.

2. In a heating system, a vapor radiator, a vapor generator communicating therewith, a liquid supply reservoir located at a lower level than said radiator and at a higher level than said generator, means providing a communicating passage between said radiator and said reservoir through which liquid flows by gravity, said reservoir being constructed and arranged to provide an air chamber above the liquid therein, a check valve constructed and arranged to substantially prevent the return of fluid from said reservoir to said generator.

5 radiator, means providing a communicating passageway between said reservoir and said generator, and means responsive to a predetermined pressure in the air chamber of said reservoir for preventing the flow of liquid therefrom to said generator.

10 3. In a heating system, a vapor radiator, a vapor generator communicating therewith, a liquid supply reservoir located at a lower level than said radiator and at a higher level than said generator, means providing a communicating passage between said radiator and said reservoir through which liquid flows by gravity, said reservoir being constructed and arranged to provide an air chamber above the liquid therein, a check valve constructed and arranged to substantially prevent the return of fluid from said reservoir to said radiator, means providing a communicating passageway between said reservoir and said generator, 15 a normally open automatic valve interposed between said reservoir and said generator, and a pressure-actuated part for automatically closing said valve whenever the pressure on the fluid in said reservoir reaches a predetermined point.

20 4. In a heating system, a vapor radiator, a vapor generator communicating therewith, a liquid supply reservoir located at a lower level than said radiator and at a higher level than said generator, means providing a communicating passage between said radiator and said reservoir through which liquid flows by gravity, means providing a communicating passageway between said reservoir and said generator, a check valve being interposed in the passage between said reservoir and said radiator constructed and arranged to substantially prevent the return of fluid from said reservoir to said radiator and means responsive to a predetermined pressure in said reservoir for preventing the flow of liquid from said reservoir to said generator.

25 5. In a heating system, a vapor radiator, a vapor generator communicating therewith, a liquid supply reservoir located at a lower level than said radiator and at a higher level than said generator, means providing a communicating passage between said radiator and said reservoir through which liquid flows by gravity, means providing a communicating passageway between said reservoir and said generator, a check valve being interposed in the passage between said reservoir and said radiator constructed and arranged to substantially prevent the return of fluid from said reservoir to said radiator and means operable within predetermined limits of pressure within said reservoir for controlling the flow of liquid therefrom to said generator and operable to prevent flow to said generator above said upper limit.

30 6. In a heating system, a vapor radiator, a vapor generator the outlet of which communicates with the inlet of said radiator, a liquid supply reservoir located at a lower level than said radiator and at a higher level than said generator, means providing a communicating passage between said radiator and said reservoir, said reservoir being constructed and arranged to provide an air chamber above the liquid, means providing communication between said reservoir and said generator, means for substantially preventing return of fluid from said reservoir to said radiator, and a check valve disposed between said reservoir and said generator and opening towards said generator.

35 7. In a heating system, a vapor generator, a

vapor radiator located above said generator, the inlet of said radiator communicating with the outlet of said generator, means for heating said generator, a liquid supply reservoir located above said generator and below said radiator and communicating with said generator, a pipe connecting said radiator to said reservoir and provided with a check valve constructed and arranged to substantially prevent the return of fluid from said reservoir to said radiator, said reservoir being provided with an air space permanently closed during normal operation and communicating with the liquid in said reservoir, and means responsive to a predetermined pressure in said reservoir for preventing the flow of liquid from 15 said reservoir to said generator.

40 8. In a heating system, a vapor generator, a vapor radiator located above said generator, the inlet of said radiator communicating with the outlet of said generator, means for heating said generator, a liquid supply reservoir located above said generator and below said radiator and communicating with said generator, a pipe connecting said radiator to an intermediate portion of said reservoir, said pipe being provided with a 25 check valve opening toward said reservoir for substantially preventing the return of fluid from said reservoir to said radiator thereby forming an air space in the upper portion thereof, said air space being permanently closed during normal 30 operation, and means responsive to a predetermined pressure in said reservoir for preventing the flow of liquid from said reservoir to said generator.

45 9. In a heating system, a vapor generator, means for heating said generator with waste gases, a vapor radiator located above said generator and communicating therewith, a liquid supply reservoir located above said generator and below said radiator and communicating with each, said liquid supply reservoir being provided with an air space permanently closed during normal operation and communicating with the liquid in said reservoir, means for substantially preventing the return of fluid from said reservoir to 40 said radiator and means responsive to a predetermined pressure in said reservoir for preventing the flow of liquid from said reservoir to said generator.

50 10. In a heating system, a vapor radiator, a vapor generator communicating therewith, a liquid supply reservoir located at a lower level than said radiator and at a higher level than said generator, means providing a communicating passage between said radiator and said reservoir, 55 said reservoir being constructed and arranged to provide an air chamber above the liquid, means providing communication between said reservoir and said generator, and means for substantially preventing the return of fluid from 60 said reservoir to said radiator.

55 11. In a heating system, a vapor radiator, a vapor generator communicating therewith, a liquid supply reservoir located at a lower level than said radiator, means providing a communicating 65 passage between said radiator and said reservoir, said reservoir being constructed and arranged to provide an air chamber above the liquid, means providing communication between said reservoir and said generator, and means for substantially preventing the return of fluid from 70 said reservoir to said radiator.

CLAUDE G. BORDEAUX.
